UNITED STATES PATENT OFFICE.

JOHN A. KOPP, JOHN G. GUENTHNER, FRANK J. WELLKAMP, AND CHARLES J. MEYER,
OF LOUISVILLE, KENTUCKY.

SWITCH.

Application filed September 28, 1925. Serial No. 59,076.

This invention relates to electrical circuit closers or switches, and has for its object the provision of a switch adapted to be mounted upon a vehicle steering wheel and operable to control any desired circuit or circuits, the particular function for which the device is designed being to control the brilliance of the headlights of the vehicle.

An important object of the invention is to provide a switch for this or an analogous purpose embodying various structural features whereby it will be within convenient reach of the operator or driver without necessitating removal of his hand from the steering wheel to effect dimming or brightening, or even extinguishing, of the lights.

A further object is the provision of a switch in which the mechanism is enclosed with the exception of the operating handle, the parts being consequently protected against injury and against the entrance of dirt, grit and the like which might interfere with the action.

A still further object is to provide a switch embodying contacts of peculiar and advantageous formation inasmuch as over-throwing will be positively prevented, the contacts being, moreover, formed integrally with the terminal elements so as to avoid likelihood of derangement, the contacts serving as stops for limiting movement of the switch arm in either direction.

An additional object is to provide a switch which will be very inexpensive to manufacture, easy and simple to install or apply and operate, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:—

Figure 1 is a plan view of a steering wheel having the switch in applied position thereon.

Figure 2 is a sectional view through the switch taken along substantially the line 2—2 of Figure 1, a portion of the steering wheel being illustrated.

Figure 3 is a top plan view of the inner member of the switch with the cover or casing and handle removed.

Figure 4 is a view taken on the line 4—4

of Figure 3, looking in the direction of the arrows, and showing a side elevation of the inner member.

Figure 5 is a horizontal section taken on the line 5—5 of Figure 2 and looking upwardly, and

Figure 6 is a detail section taken on the line 6—6 of Figure 3 and illustrating the contact construction.

Referring more particularly to the drawings, the letter A designates, generally, a steering wheel upon which it is intended that the switch be mounted, the wheel including the usual hub portion from which radiate spokes B carrying the rim C, the intention being to mount the switch upon one of the spokes as indicated in Figure 1.

In carrying out the invention we provide a base member 10 of suitable insulating material and of any desired size and shape, which base member has one side cut away, as indicated at 11 so as to define an opening or space 12 beneath a disk 13, likewise of insulating material mounted upon the base member 10 and secured thereto as by means of a bolt or screw 14 which, in the present instance, is represented as projecting beyond the bottom of the base and screwed into a suitably tapped hole 15 in one spoke of the wheel. It is also desirable to use a similar screw or bolt 16 passing through another part of the base and likewise screwed into a tapped hole 17 in the wheel spoke. It will be observed that the screw 14 performs the additional function of preventing rotation 80 of the disk 13 with respect to the base 10.

Located at the center of the disk 13 is the rotatable switch arm structure indicated generally by the numeral 18, which arm is necessarily constructed of metal and formed with a hub portion 19 carrying an outwardly extending arm 20, which has its edges preferably beveled off oppositely as clearly indicated in Figure 6, for a reason to be explained. The hub portion 19 is formed 100 with a reduced cylindrical extension 21 journally mounted through a suitable hole in the disk 13, the arm being held in place by a screw 22 which passes through a stop washer 23 and into a tapped hole in the extension 21. Above the central hub portion 19 is a cylindrical extension 24 terminating in a reduced angular extension 25.

Carried by the disk 13 and located at spaced points are contacts 26 which are sim-

ilar in construction. Each contact is formed as a metallic body 27 having a substantially U-shaped head 28 adapted to receive the switch arm 20, the inner corners of the ends 5 of the arms of the U being preferably rounded off as indicated at 29 to provide a flaring entrance to the space within the U-shaped head, for facilitating passage of the switch arm into the space, as clearly indicated in 10 Figure 6. The metallic body 27 is further formed with a reduced threaded extension or shank 30. The two contact members 26 are arranged with the heads 28 in opposite relation, as shown in Figure 3, so that the 15 switch arm 20 may enter them at the ends of its movement. The shanks 30 of course pass through suitable holes in the disk 13 and carry securing nuts 31. These shanks constitute terminals with which are connect- 20 ed terminal lugs 32 on the ends of conductors 33 which are preferably formed into a loom 34. The loom further includes a conductor 35 equipped with a terminal lug 36 engaged and held by the screw 22 provided 25 for holding the switch arm assembly in place. The space 12 within the base defined by cutting it away is for the accommodation of the conductors 33 and 35, as well as the binding nuts employed in connection therewith. 30

The above described parts are enclosed within a casing 37 which may be of any suitable material, but which is here represented as metallic and provided with a lining 38 of insulating material. The casing is frictionally engaged upon the base member 10 and fits snugly thereon and upon the disk 13. At its center the casing is formed with a hole 39 within which the cylindrical extension 24 is journaled, the angular extension 25 of course projecting beyond the casing and carrying a handle 40 having a suitable opening therethrough conformingly engaged upon the angular extension 25. A 45 screw 41 is used for holding the handle in place, this screw being threaded into the extension 25.

Under ordinary circumstances, or when it is so desired, the switch arm 20 may be held 50 in neutral position by means of a curved up-standing projection 42 formed integrally upon the disk 13 at a point midway between the contacts 26, the arm 20 being resilient so that when sprung up onto the projection 55 42 it will remain in such position by friction, so that a positive turning movement of the handle 40 must be given to move the switch arm 20 off from the projection 42 and into engagement with the selected contact 26.

60 While the uses of the device are many, it is particularly well adapted for use in controlling headlights of an automobile, in which event the conductor 35 might be connected with the source of current of the car and the conductors 33 connected with

the proper terminals provided for whatever wiring, resistance, etc. is provided in connection with the headlights. This use is mentioned by way of illustration, and when the switch is employed for such a purpose, it is quite obvious that it will be a simple and easy matter to move the handle 40 to bring the switch arm 20 into engagement with either contact 26 for supplying current to either of two circuits. An advantage is that the handle 40 is located in such position as to be within convenient reach of the operator or driver who may control the switch without any necessity for removing his hand from the rim of the steering wheel, where it should be kept in accordance with the dictates of safety. Owing to the fact that the heads 28 of the contact members 26 are intended to be somewhat resilient, and owing to the tapering of the opposite sides of the switch arm, it is clear that when the switch arm is in engagement within either contact 26 it will be frictionally held and prevented from accidentally slipping out, this being another safety feature in that unintentional extinguishing the lights would not occur. In view of the fact that all the parts with the exception of the handle are enclosed, it will be seen that there is no opportunity for dirt, grit or the like to enter and interfere with the action. 95

While we have shown and described the preferred embodiment of the invention, it should be understood that we reserve the right to make such changes in the form, 100 construction and arrangement of parts as will not depart from the spirit of the invention or the scope of the subjoined claims.

What is claimed is:—

1. A switch of the character described 105 comprising a base of insulating material, a casing connected therewith, said base having a portion cut away to define a space, a disk secured upon the base and extending entirely across the interior of the casing, a 110 switch arm assembly including a hub portion rockably mounted in the disk and casing, and an elongated arm secured to the hub portion above the disk and within the casing, a binding screw located in said space 115 beneath the disk and secured to the lower end of said hub portion, said hub portion terminating at its upper end in an extension projecting beyond the casing, a handle on said extension, a pair of contacts mounted 120 on said disk in the path of said arm, other binding screws located in said space beneath the disk and connected respectively with said contacts, said casing having an opening in one side so that conductors may pass into 125 said space beneath the disk and be connected with the respective binding screws.

2. A switch of the character described 130 comprising a base of insulating material, a casing connected therewith, said base having

a portion cut away to define a space, a disk secured upon the base and extending entirely across the interior of the casing, a switch arm assembly including a hub portion rockably mounted in the disk and casing, and an elongated arm secured to the hub portion above the disk and within the casing, a binding screw located in said space beneath the disk and secured to the lower end of said hub portion, said hub portion terminating at its upper end in an extension projecting beyond the casing, a handle on said extension, a pair of U-shaped contacts arranged in opposed relation in the path of said arm, each of said contacts having a stem integral-

ly therewith and extending through the disk, the lower end of said stem constituting a binding screw, said casing having an opening in one side, and conductors extending through the opening into said space beneath the disk and connected with the respective binding screws. 20

In testimony, that we claim the foregoing as our own, we have hereto affixed our signatures.

JOHN A. KOPP.
